PRINTER'S QUOIN LOCK

Elmer Mason Foote, Elmira, N. Y., and Freeman Barney, Spring Lake, Mich., assignors to The Challenge Machinery Company, Grand Haven, Mich., a corporation of Michigan

Application October 22, 1951, Serial No. 252,494

2 Claims. (Cl. 254—42)

1

This invention relates to printers' quoins and, more particularly, concerns locking a printer's quoin against accidental or other release thereof after it has been adjusted to lock type bars, electrotypes or other materials, from which printing is made, in a form.

Printers' quoins, in a form are subject to heavy service and must retain the locked type bars and the like so that they will not move or otherwise become ineffective. The quoins which are of the type shown in United States Letters Patent No. 2,501,949, granted March 28, 1950, operate by wedging action of two inclined planes riding upon each other on two members which are carried by a somewhat elongated supporting or body member, one of said members being movable longitudinally and the other transversely of said supporting member. The operation of the quoin is by moving the longitudinally movable member so that by the action of the engaging inclined planes on the two members the transversely movable member is moved outwardly. When the quoin has been operated to lock the form ready for printing, the present invention has for its object and purpose the provision of simple, practical and operative means for rendering impossible any longitudinal movement of the longitudinal member of the quoin, thus, preventing release of the quoin if it should tend to occur under vibration or shocks to which subjected in printing.

To these ends, we have provided embodiments of the invention which positively serve the purpose of insuring that the quoin will remain in its holding or locking position until it is to be released. The structures which embody the invention are readily applied to printers' quoins like those in the patent mentioned and, in the preferred form, remain with the quoin in either its operative or inoperative position so as not to become disassociated therefrom and lost.

An understanding of the invention may be had from the following description, taken in connection with the accompanying drawing embodying forms of our invention, in which drawing,

Fig. 1 is a plan view of the quoin at one end portion thereof illustrating our invention.

Fig. 2 is a horizontal section and plan, the plane of the section being substantially on the line 2—2 of Fig. 3.

Fig. 3 is a transverse vertical section through the quoin showing the lock in its operative position.

Fig. 4 is a like view showing the lock withdrawn and in inoperative position.

2

Fig. 5 is a view, similar to Figs. 3 and 4, showing another form of the invention but one which is not preferred, and

Fig. 6 is a somewhat enlarged perspective view of the quoin lock bolt used with the quoin of the aforesaid patent, or quoins of similar structure.

Like reference characters refer to like parts in the different figures of the drawings.

In the construction of a printer's quoin, a channel member having a web 1, and upper and lower spaced flanges 2 and 3 is provided and forms a housing for the assembly. Within the channel member, two elongated wedge members or bars are housed. The inner bar 4, at its outer side, is provided with a plurality of consecutive wedge surfaces 5 from one end thereof to the other. Bar 4 is longitudinally movable with respect to the channel member by which carried and in which it is housed. The member 4, between its ends, is formed with a short rack having consecutive teeth 6, adapted to be engaged by the inserted end of a removable key which in cross-section is like a pinion, and which key on being turned manually will move the inner wedge member 4 longitudinally in accordance with the direction that the key is turned.

The other or second wedging bar 7 is also elongated, of substantially the same length as the described channel and is somewhat longer than the wedging bar 4. At its inner side it has cooperating inclined faces 8 adapted to ride or bear against the faces 5 of the bar 4. The outer bar 7 is provided with pins 9 extending therethrough, the ends of which are received in slots 10 transversely located in flanges 2 and 3 of the channel member. The upper channel 2 has an entrance 13 for the insertion of the key which operates the rack 6, and the key is guided by a vertically positioned arcuate guide 14, as shown in Fig. 2, and maintained in engagement with the rack when inserted. Slot 11 lengthwise of the flange 2 and pin 12 on bar 4 cooperates to limit the movement of the bar 4 and to secure such bar from disconnection.

In one form of the invention, shown in Fig. 5, the upper flange 2 may have a vertical opening therethrough over the rack 6, through which a headed pin 15 may be inserted after the quoin has been operated to force bar 7 outwardly to its form locking position. Such structure, however, is not preferred as the pin is liable to be lost. In use, it is inserted through the opening in the flange 2, the pin passing between two of the teeth 6, the opening located a little to one side of the key insertion opening 13.

In the preferred structure shown the outer bar 7 at its upper side and a short distance to one side of the opening 13 is provided with a shallow transverse groove 16. A locking bolt is made from a single piece of flat metal of the form best disclosed in Fig. 6. The outer end of the bolt is turned upwardly in a flange 17, from the lower edge of which two spaced apart horizontal members 18 extend. The metal between the two spaced members 18 is struck from the plate, turned upwardly at the inner ends of the parts 18 in a short vertical member 19, and continued in a horizontal section 20 which terminates in an angularly shaped lip 21 as shown. The lip 21 lies over an integral connecting part 22 of the plate at the other ends of parts 18. From the edge of part 22 two spaced teeth 23 project, shaped and formed and so spaced from each other that they are adapted to embrace one tooth 6 of the rack and enter the spaces between the next adjacent teeth 6, one at each side of the tooth which is embraced thereby.

When assembled with the rest of the quoin in the shallow groove 16, the upwardly extending portion 19 passes through an opening 24 made in the upper flange 2, and the detent lip 21 of the bolt 20, extends over the upper side of such flange 2. In outer position, as in Fig. 4, the teeth 23 are withdrawn and do not connect with the teeth 6 of the rack. In such position by operation of the key inserted at the opening 13, the quoin may be operated to move the outer member 7 outwardly in locking a form. When the form is locked, the locking bolt is pushed inwardly to the position shown in Fig. 3, whereupon the latching detent 21 reaches a second opening 25 in line with the opening 24 in the upper flange 2, the teeth 23 having been moved into engaging locking position with respect to the rack key 6 as shown in Fig. 2. When the quoin is to be released, the locking bolt is pulled back as in Fig. 4, whereupon the rack engaging key may be inserted through the opening 13 to release the quoin.

With the structure described, a quoin when it has been expanded to serve its purpose, is insured against accidental or any other unwanted release until the locking bolt has been withdrawn from its holding connection with the key 6. The bolt described is assembled with the quoin and is inseparable therefrom after the assembly is complete. The structure described is practical and effective, and by simple and novel operation insures that the quoin shall remain locked in its expanded operative position and not release or be released therefrom until such release is wanted.

The invention is defined in the appended claims, and is to be considered comprehensive of all forms of structure coming within their scope.

We claim:

1. In a printer's quoin, having an elongated body of channel form with an upper and lower horizontal flange and a vertical web integrally connecting said flanges at common edges thereof, an elongated wedging member against the inner side of the web mounted for longitudinal move-

ment between the flanges, a second wedging member against the first wedging member, mounted for and held to transverse movements away from or toward the first wedging member, said first wedging member having a rack with spaced teeth between its ends, the improvement comprising, a lock bolt of thin metal located under the upper flange of the body, said second wedging member having a shallow slot in its upper side, transversely of the length of said member, in which the bolt is slidably mounted, said bolt at its inner end having a projection adapted to enter between teeth of the rack in one position of the bolt and be clear of the rack in another position, and a detent extending upwardly from the bolt between the ends thereof, said upper flange having an opening for passage of the detent, said detent, above said flange, having a generally horizontal extension bearing against the upper side of the upper flange.

2. In a printer's quoin, having an elongated body of channel form with an upper and lower horizontal flange and a vertical web integrally connecting said flanges at common edges thereof, an elongated wedging member against the inner side of the web mounted for longitudinal movement between the flanges, a second wedging member against the first wedging member, mounted for and held to transverse movements away from or toward the first wedging member, said first wedging member having a rack with spaced teeth between its ends, the improvement comprising, a lock bolt of thin metal located under the upper flange of the body, said second wedging member having a shallow slot in its upper side, transversely of the length of said member, in which the bolt is slidably mounted, said bolt at its inner end having a projection adapted to enter between teeth of the rack in one position of the bolt and be clear of the rack in another position, and a detent extending upwardly from the bolt between the ends thereof, said upper flange having an opening for passage of the detent, said detent, above said flange, having a generally horizontal extension bearing against the upper side of the upper flange.
